Alvin E. Dutcher
ATTORNEY

UNITED STATES PATENT OFFICE

DAVID HENRY WARD, OF SEATTLE, WASHINGTON

DISPLAY APPARATUS

Application filed August 25, 1930. Serial No. 477,718.

My invention has for its object to improve on the mechanism disclosed in my Patent No. 1,090,668 of March 17, 1914. In the patented mechanism the sign material, housed in a circular case under pressure, lost its resiliency and became shaped to the case with no means for remolding it so as to hang straight and it was very limited in size owing to the principle of disks as a means for operation; my present invention therefore seeks to overcome these difficulties.

Further, it is an object of the invention to provide a display apparatus that is particularly useful in the exhibiting of signs of large dimensions in a frame or case of very shallow depth and to provide such an apparatus as is particularly useful in the display of wall paper and the like.

Further, it is an object to provide a new and improved means to mount the sheets on endless chains which pass over rollers for feeding purposes.

Further, it is an object to provide for close operation in the falling of the upper portion of the sign sheet exposed and the lower portion of the sign sheet following.

Further, it is an object of the invention to provide an exhibitor in which the sheets are folded crosswise so that one fold is larger than the other, the shorter fold being at the bottom when the sheet is undergoing exposure.

Further, it is an object to provide means to attach the sheet at the place of fold to the carrier chains at such intervals as will insure the release of the upper portion of the exposed sheet and the lower portion of the sheet following at the same time.

Further, it is an object of the invention to provide mechanism whereby when the sheet arrives at its exposed position, the short leaf of the following sheet will be free to follow the long leaf of the preceding sheet toward the exhibiting position while the longer leaf of said following sheet will still be held by pressure of the ironing rollers.

Other objects will in part be obvious and in part be pointed out hereinafter.

To the attainment of the aforesaid objects and ends, the invention still further resides in

the novel details of construction, combination and arrangement of parts, all of which will be first fully described in the following detailed description, then be particularly pointed out in the appended claims, reference being had to the accompanying drawings, in which:—

Figure 1 is a perspective view of the invention.

Figure 2 is a vertical longitudinal section of the same.

Figure 3 is a detail perspective view of the upper portion the case being broken away and the sheets removed.

Figure 4 is a detail view showing the means of attaching the sheet to the chain.

Figure 5 is a detail perspective view of the sheet showing the attaching hooks at the fold and the cords for connecting the adjacent sheets.

In the drawings, in which like numerals of reference indicate like parts in all of the figures, 1 represents the case having the front opening 2 and being mounted on a suitable base 3.

About midway of the height of the case there is provided an operating shaft 4 having an outside wheel or handle 5 by means of which it may be turned and carrying sprockets 6 within the case.

A master roller 7 is mounted at the top of the case and is provided with suitably spaced chain grooves 8 for the endless chains 24 which pass over the sprockets 6 and lie in the grooves 8.

9 designates an intermediate roller located beneath and spaced some distance from the master roller 7, the intermediate roller 9 also having chain grooves 10 for the reception of the chains 24. These chains, however, do not take around the intermediate roller as they do the master roller.

An ironing or pressing roller 11 is provided in association with the rollers 7 and 9, the ironing roller 11 being mounted on spring rods 12, at one end of which the shaft ends 13 of the roller 11 are carried. The other ends of the spring rods 12 are hooked to the back of the case.

The sheets which are to be exhibited are

folded over along an edge 16 so as to leave a long leaf 14 and a short leaf 15. If desired the sheets may be reinforced at the fold as at 25 either by gluing a binder strip over the 5 fold or the sheet can be made in two leaves, one of which will be folded over the edge of the other and pasted thereto as indicated in Figure 5.

17 designates hooks which are adapted to 10 engage in an eye of the links of the chains 24, the hooks having triangular portions 18 by means of which the hooks may be secured to the sheets. This is preferably done by slotting the sheets or the reinforcing binder 15 as at 19 and passing an adhesive tape 20 through the slots and through the hook eyes 18 and securing the ends of the strips by their own adhesion to the sheet or binder strip.

Each leaf of the sheet adjacent its free end 20 is provided with a three-sided slot 21, leaving a dove-tail shaped tongue 22 over which the looped end of a connecting cord 23 may be passed for tying together the adjacent leaves of adjacent sheets.

25 In placing the sheets on the conveyor chains the folded edges are so spaced apart that the free edge of the long leaf 14 and the free edge of the next adjacent short leaf 15 of the next adjacent sheet will match up, see Figure 2, 30 in order that when the sheets pass from under the ironing roller 11 the long leaf of the advance sheet and the short leaf of the following sheet will be released together and permitted to drop down through the opening 2 to exhibit 35 the following sheet, the two leaves, i. e., the long leaf of the exhibited sheet and the short leaf of the following sheet, being tied together by the flexible connection 23, will be caused to fall simultaneously and thus insure 40 proper exhibition of the matter contained on the sheets.

From the foregoing it will be seen that by turning the operating shaft in one direction the sheets are brought over the master roller 45 from the back of the case, ironed out between the master and intermediate rollers by the ironing roller so that when the sheet is in the exhibiting position it will be straight and smooth throughout its length and will not retain 50 the kinks and bends it assumes in passing around the master roller.

From the foregoing description, taken in connection with the accompanying drawings, it is thought the complete construction, operation and advantages of my invention will 55 be clear to those skilled in the art to which it relates.

What I claim is:

1. In exhibitors of the character described, 60 a case having a window, an endless chain sheet-conveyor mounted in the upper portion of the case and comprising an operating shaft with sprockets, an upper master roller, an intermediate roller, said rollers having chain-receiving portions, endless chains taking 65 receiving portions, end

around said master roller and said sprockets, and a set of transversely folded sheets hingedly connected at the folded edge to said chains, means combined with said rollers for ironing out said sheets.

2. In exhibitors of the character described, a case having a window, an endless chain sheet-conveyor mounted in the upper portion of the case and comprising an operating shaft with sprockets, an upper master roller, an intermediate roller, said rollers having chain-receiving portions, endless chains taking around said master roller and said sprockets, and a set of transversely folded sheets hingedly connected at the folded edge to said chains, means combined with said rollers for ironing out said sheets, said sheets each comprising a long leaf and a short leaf, said sheets being so spaced on the chains that the long leaf of one sheet and the short leaf of the next succeeding sheet will be released from said ironing means simultaneously.

3. In exhibitors of the character described, a case having a window, an endless chain sheet-conveyor mounted in the upper portion of the case and comprising an operating shaft with sprockets, an upper master roller, an intermediate roller, said rollers having chain-receiving portions, endless chains taking around said master roller and said sprockets, and a set of transversely folded sheets hingedly connected at the folded edge to said chains, means combined with said rollers for ironing out said sheets, said sheets each comprising a long leaf and a short leaf, said sheets being so spaced on the chains that the long leaf of one sheet and the short leaf of the next succeeding sheet will be released from said ironing means simultaneously, and means connecting the adjacent leaves of adjacent sheets together.

4. In exhibitors of the endless chain carrier type, a sheet folded transversely to provide a short leaf and a long leaf, attaching hooks located at the folds of the sheet for securing the same to the chains of the carrier, a binder strip secured to the sheet adjacent the fold thereof, and adhesive strips passing through slots in the binder strip and stuck to the strip for mounting said hooks on said sheet.

5. In exhibitors of the endless chain carrier type, a sheet folded transversely to provide a short leaf and a long leaf, attaching hooks located at the folds of the sheet for securing the same to the chains of the carrier, a binder strip secured to the sheet adjacent the fold thereof, and adhesive strips passing through slots in the binder strip and stuck to the strip for mounting said hooks on said sheet, said sheet also having dove-tail slits adjacent the free edges of the leaves thereof for receiving flexible cords to connect the leaves of adjacent sheets together.

6. In exhibitors of the class described, a case having a window, an endless-chain sheet-

conveyor mounted in the case, and including an operating shaft with sprockets, a conveyor chain taking around said sprockets, and a master roller around which said conveyor 5 chain passes, a set of transversely folded sheets each having a long leaf and a short leaf, means flexibly connecting said sheets at the fold edge to said chains, and means cooperating with said conveyor for holding 10 the longer leaf against dropping while the shorter leaf of the sheet is in the lowered position during exhibition.

7. In exhibitors of the class described, a case having a window, an endless-chain sheet- 15 conveyor mounted in the case, and including an operating shaft with sprockets, a conveyor chain taking around said sprockets, and a master roller around which said conveyor chain passes, a set of transversely folded 20 sheets each having a long leaf and a short leaf, means flexibly connecting said sheets at the fold edge to said chains, and means cooperating with said conveyor for holding the longer leaf against dropping while the shorter 25 leaf of the sheet is in the lowered position during exhibition, said holding means including an ironing roller associated with said conveyor.

DAVID HENRY WARD.
